UNITED STATES PATENT OFFICE.

WARREN C. DYER, OF ST. LOUIS, MISSOURI.

BATHING APPLIANCE.

Application filed January 25, 1921. Serial No. 439,806.

To all whom it may concern:

Be it known that I, WARREN C. DYER, a citizen of the United States, residing at St. Louis, in the county of St. Louis and State 5 of Missouri, have invented new and useful Improvements in Bathing Appliances, of which the following is a specification.

This invention relates to bathing appliances and more particularly to a device, an 10 object of which is to enable a bather to easily and satisfactorily cleanse or bathe his own back.

Another object of this invention is to provide a bathing apparatus, as specified, which 15 comprises a bowed handle having a gripping portion carried thereby comprising a stationary gripping plate and an adjustable or movable gripping plate, the said plates being adapted to securely grip a bath brush, 20 sponge, towel or the like, and also to provide means for securely holding the adjustable gripping plate in adjusted position.

Other objects of the invention will appear 25 in the following detailed description and in the accompanying drawings wherein:

Fig. 1 is a side elevation of the improved bathing appliance.

Fig. 2 is a front elevation of the bathing 30 appliance.

Fig. 3 is a vertical section through the bathing appliance taken on the line 3—3 of Fig. 2.

Fig. 4 is a cross section taken on the line 35 4—4 of Fig. 2.

Referring more particularly to the drawings, the improved bathing appliance comprises a handle 1 which is formed of wires 2 and 3 twisted together for the major portion of the length of the handle 1. A hand grip 4 is mounted upon one end of the handle 1 and the handle 1 is bent into, substantially, the shape of an inverted U, as clearly shown in Fig. 2 of the drawings having the ends of the wires 2 and 3, remote from the hand grip 4, extending parallel and in engaging relation, to a point in proximity to their ends at which point they are bent outwardly to space the terminal lengths 5 and 6 in parallel spaced 50 relation. A gripping plate 7 is rigidly attached, by means of collars 8, to the ends of the parallel portions 5 and 6. The gripping plate 7, preferably has an upstanding flange 9 along one edge and upstanding

flanges 10 along each end, the said flanges 55 being provided to permit effective engagement between the plate 7 and a bath brush. A second gripping plate 11 is adjustably supported by the parallel terminal lengths 5 and 6, it being connected to these lengths 60 by collars 12, one at each end of the plate 11. A stem 13 is connected to the plate 11 and extends longitudinally of the parallel engaging portions of the wires 2 and 3 of which the handle 1 is formed, the concave 65 space between the parallel engaging lengths forming a guide for the stem 13, as clearly shown in Fig. 4 of the drawings. A metal strap 14 is carried by the parallel engaging lengths of the wires 2 and 3 and it has a binding cam 15 eccentrically pivoted thereto. The binding cam 15 preferably has a concave perimeter as shown at 16, and a handle 17 is connected to the binding cam for rotating it upon its pivot to bring it 70 into clamping engagement with the stem 13, to clamp the stem between the cam 15 and the parallel engaging lengths of the wires 2 and 3 to securely hold the adjusted 75 clamping plate 11 in position.

The handle 1 is bent or curved into, substantially, the shape of an inverted U to facilitate the bathing and drying of the portions of a person's back which are not successfully reached without the use of a 80 bathing appliance and the handle 1 is of sufficient rigidity to permit it to be placed over the shoulder of the user with a hand grip 4 at the front while the back may be thoroughly bathed or dried with a sponge, 85 brush or towel, securely held in place by the clamping plates 7 and 11. Owing to the particular shape of the bathing appliance all parts of the user's back may be conveniently and satisfactorily reached.

It is, of course, to be understood that the invention may be constructed in various other manners and the parts associated in different relations and, therefore, I do not desire to be limited in any manner except 90 as set forth in the claims hereunto appended.

Having thus described the invention what I claim is:

1. A bathing appliance comprising a handle having parallel terminals, a stationary gripping plate secured to said terminals, an adjustable gripping plate slidable on the terminals, and a stem projecting from the 105

adjustable plate, and a device for forcing the members, a stem projecting from the said stem into tight frictional engagement with the handle for holding the adjustable gripping plate in position.

5. A bathing appliance comprising a wire handle terminating in a pair of spaced members, a stationary gripping plate secured to the members, an adjustable plate slidable on

adjustable plate and moving parallel to the handle, and a cam device connected to the handle to force the stem into tight binding action with the handle.

In testimony whereof I affix my signature.

WARREN C. DYER.
